UNITED STATES PATENT OFFICE.

JOHN L. DAWES, OF PITTSBURGH, PENNSYLVANIA.

DESIGN FOR AN ADVERTISING OR SIGN STRUCTURE.

43,353.

Specification for Design.

Patented Dec. 24, 1912.

Application filed October 8, 1912. Serial No. 724,659. Term of patent 7 years.

To all whom it may concern:

Be it known that I, JOHN L. DAWES, a resident of Pittsburgh, Allegheny county, Pennsylvania, have invented a new, original, and ornamental Design for an Advertising or Sign Structure, of which the following is a specification, reference being had to the accompanying drawing, forming part of this specification, in which the figure is a perspective view of a structure embodying my design.

I claim:

The ornamental design for an advertising or sign structure, as shown.

In testimony whereof, I have hereunto set my hand.

JOHN L. DAWES.

Witnesses:

C. P. BYRNES,
H. M. CORWIN.
